UNITED STATES PATENT OFFICE.

MAY F. DENIS, OF EAST ORANGE, NEW JERSEY.

DESIGN FOR A BRUSH AND BROOM HOLDER.

58,724.

Specification for Design.

Patented Aug. 30, 1921.

Application filed January 25, 1921. Serial No. 439,863. Term of patent 3½ years.

To all whom it may concern:

Be it known that I, MAY F. DENIS, a citizen of the United States, residing at East Orange, in the county of Essex and State of New Jersey, have invented a new, original, and ornamental Design for a Brush and Broom Holder, of which the following is a specification, reference being had to the accompanying drawing, forming part thereof.

In the drawings:—

Fig. 2 is a top plan view of the same.

I claim:—

The ornamental design for a brush and broom holder, as shown.

MAY F. DENIS.
